ATTRITION MILL

Frank C. Vaughan, Richmond, Va., and Maurice D. Woodruff, Springfield, Ohio, assignors to The Bauer Bros. Company, Springfield, Ohio, a corporation of Ohio

Filed Oct. 29, 1953, Ser. No. 389,054
8 Claims. (Cl. 241—256)

This invention relates to mills and more particularly to mills of the disc type for the abrading and refining of pulp and other type of fibrous materials.

The object of the invention is to improve the construction as well as the means and mode of operation of disc mills whereby they may not only be economically manufactured, but will be more efficient in use, semi-automatic in operation, uniform in action, having a minimum number of working parts yet provide for easy access, and be unlikely to get out of repair.

The object of the invention is to achieve a reorganization of mill structure, with the view of providing better balance, easier and more accessible means of adjustment and a more reliable and trouble free operation.

More specifically, it is an object of the invention to provide a simple and effective means of gaining access to the refining chamber wherein the material is reduced or ground between opposing discs.

Another object of the invention is to improve the balance and operational characteristics of the mill by mounting the rotating disc between spaced apart bearings.

A further object of the invention is to provide for variation in clearance between the discs through adjustment of the main driving shaft.

Still another object of the invention is to utilize hydraulic means in the adjusting of the shaft and as a shock absorber in the presence of unrefinable material between the discs.

A still further object of the invention is to make a dual use of a thrust bearing on the shaft whereby it may serve also as a piston in the described hydraulic movements of the shaft.

A still further object of the invention is to permit rotary adjustment of the stationary disc as an aid to more convenient servicing and access to the mill.

A further object of the invention is to provide a disc mill embodying the advantageous structural features, the inherent meritorious characteristics and the mode of operation herein set forth or their equivalents.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

In the accompanying drawings, wherein is shown one but not necessarily the only form of embodiment of the invention,

FIG. 1 is a view in longitudinal section of a disc mill in accordance with the illustrated embodiment of the invention;

FIG. 2 is an end view of the mill of FIG. 1, showing the stationary disc in an operating position;

FIG. 3 is a fragmentary view similar to FIG. 2, showing the stationary disc rocked a distance of about ninety degrees from the position of FIG. 2; and

FIGS. 4 and 5 are views in cross section taken substantially along the respective lines 4—4 and 5—5 of FIG. 1.

Like parts are indicated by similar characters of reference throughout the several views.

Referring to the drawings, a disc mill in accordance

2

with the illustrated embodiment of the invention comprises a base 10 from which rises a support housing 11. The latter provides spaced bearing supports 12, and an intermediate relatively large refining area receiving grinding discs 13 and 14. The discs 13 and 14 are arranged in coaxial adjacent relation and have detachable face plates 15 and 16 which coact to reduce material introduced therebetween. A supplemental housing 17 surrounds the discs 13 and 14 forming therein a closed chamber 18. The material is applied to the discs 13 and 14, at the center thereof, by an inlet tube 19, and, in response to relative rotation of the discs 13 and 14 the material passes radially outward between the plates 15 and 16, discharging into the chamber 18 and flowing out of the mill by way of a communicating outlet tube 21.

The disc 14 is a fabricated element, made water-tight for purposes of better balance. It is secured to shaft 23 which is disposed in parallel relation to the base 10 coaxially of the discs 13 and 14. The shaft 23 extends axially through the discs 13 and 14 and is supported in bearings on opposite sides of the disc assembly for purposes of balance and better distribution of bearing load. One bearing for the shaft 23 is contained in a housing 24 installed in the support 11 and comprises a grooved sleeve 25 on the shaft, a relatively elongated race 26 on the interior of the housing 24, and interposed roller bearings 27. One end of the shaft 23 extends through and beyond the bearing housing 24 and is adapted for operative engagement with a suitable rotary driving mechanism.

The opposite end of the shaft 23 is received in a sleeve 28 which has a rotatable bearing in a concave surface 29 of the support 11. A bearing housing 31 has a press fit in the sleeve 28 and provides the other bearing for the shaft 23, such bearing including an elongated race 33, and bearings 34 located in a grooved sleeve 35 fastened to the shaft.

The sleeve 28 is integrally united, through an adapter super structure 36, with the disc 13. An overlying clamp member 37 is arranged in complementary relation to the concave surface 29 alternatively to grip and hold the sleeve 28 against rotation or to release the sleeve for rotation. Such adjustments are accomplished by tightening or loosening bolts 38 (FIG. 4) which are normally tightened so that the sleeve 28 and its associated parts, including the disc 13, are relatively stationary.

In response to rotation of the shaft 23, the disc 14 rotates relatively to the disc 13 to effect the refining or reduction of the material supplied by way of inlet 19. The material entering by way of inlet 19 is constrained to follow a path centrally of the discs 13 and 14, and radially outward between the plates 15 and 16 thereon, by an arrangement of baffles 39 and 41 and by a seal 42 which inhibits flow of the material along the shaft 23 into the sleeve 28.

The aforementioned auxiliary housing 17 is in part defined by a ring 43 in surrounding spaced relation to the discs 13 and 14 and resting at its one end on the housing 17 proper. The opposite end of the ring 43 is operatively engaged with an annulus 44 extending from and forming a part of the adapter 36. A circumferential series of attachment means are provided on the ring 43 and the annulus 44, such means including brackets 45 on the ring 43, brackets 46 on the annulus 44 and interconnecting tie members 47. The ring 43 normally occupies a position overlying the space between the annulus 44 and the housing 17 proper. The chamber 18 accordingly is closed and the ring 43 may be considered to be in a closed position. Upon release of the connection afforded by the tie members 47 the ring 43 may be slid axially to a position as indicated in dotted lines in FIG. 1. This may be considered its open position since the chamber 18 is open

and the discs 13 and 14 are accessible for cleaning or servicing.

Due to the size and weight of the machine, and particularly the plates 15-16 there is presented a problem of access and convenience in the servicing and maintenance of the present machine. Problems of substantially the same magnitude are presented in mills presently being used and heretofore there has been no solution offered. In the present disclosure the so-called "fixed" or non-rotating plate 13 and its associated face pieces 15 are so mounted through the medium of the tubular sleeve 28 that they may be rotated through a limited range to improve the servicing and maintenance problem. After release of the connections 45-47 and movement of the ring 43 to its open position, the adjustment bolts 38 are loosened. The tubular sleeve 28 is thereby released for rotary motion relative to the support 11 and the enclosing cover or clamp member 37. The plate or disc 13 and its associated elements may then be manually rotated a distance of approximately 90° in either direction from its normal position as shown in FIG. 2. FIG. 3 shows the plate 13 and associated elements rotated in one direction from "normal." Thus the face plate 15 which normally comprises individual sectors secured to the plate 13 may be easily removed a sector at a time for repair or replacement. The uppermost sectors are removed while the plate 13 is in "normal" position, after which the plate 13 is rotated in first one direction and then the other to bring the lowermost sectors of face plate 15 into the upper half of the housing for easy removal.

The left hand or inner end of the shaft 23 terminates within the sleeve 28 and has a collar 48 secured thereto by means including a nut 50. The collar 48 is a part of a thrust bearing assembly 49 which further includes a surrounding sleeve 51, two sets of shoe elements 52 and end plates 53 and 54. The bearing 49 is a commercially available unit known as a "Kingsbury" bearing and functions to absorb endwise thrust upon the shaft 23 without material interference with rotation of the shaft. The sleeve 51 is connected, as by a key 55, with the sleeve 28 and further is grooved to separate the shoes 52 from one another and to prevent their rotation with the collar 48.

The bearing 49 is disposed in a chamber 56 closed at its one end by a disc 57 abutting the bearing bushing 31 and closed at its other end by a plate 58 held in place on the end of the sleeve 28 by a closure cap 59. A screw post 61 has a screw threaded mounting in the cap 59 and extends through the plate 58 into the chamber 56 to define a limit of longitudinal motion for the bearing 49 in one direction. A non-rotating sleeve 62 is secured to plate 54 and forms a sliding seal with plate 57 and with the sleeve 28 and plates 54 and 57 defines the right hand end of chamber 56.

The chamber 56 functions as a hydraulic pressure chamber, with the bearing 49 serving as a piston therein for the purpose of moving the shaft 23 in an endwise or axial direction to effect a relative approaching or withdrawing motion of the discs 13 and 14. Such motion of the shaft is permitted by the aforementioned elongated races 26 and 33 in the bearing housing 24 and 31. The chamber 56, on opposite sides of the bearing 49 is connected in a manner not here shown in a hydraulic circuit.

In defining the initial position of adjustment of the discs 13 and 14, the screw post 61 is retracted out of an operational position. The hydraulic circuit then is adjusted to admit pressure fluid through passages 65 to the chamber 56 on the right-hand side of the bearing 49 and to connect the opposite or left-hand end of the chamber through passage 67 to a supply tank (not shown). As a result, the piston bearing 49 and the shaft 23 move leftward to effect an approaching motion of the disc 14 toward the disc 13. This motion continues until the plate 16 contacts the plate 15 which will make a sound ordinarily audible to the operator. The leftward motion of the shaft 23 and associated parts is halted by engage-

ment of the plates 15 and 16 and by turning a wheel 63, post 61 is advanced into engagement with the plate 53. This provides a "zero" setting of the plates 15-16 and a reference point from which other settings of plate clearances are made. To set the plates 15-16 to desired clearance, pressure fluid is admitted to the chamber 56 on the left side thereof, i.e., intermediate plates 53-58, to thereby move shaft 23 and associated plate 14 toward the right. Thereupon the post 61 is advanced the amount of the desired clearance and locked by appropriate rotation of the lock nut 64. Pressure fluid is then admitted to the right side of chamber 56 and the bearing assembly 49 caused to travel to the left until it is stopped by plate 53 contacting post 61, to maintain the minimum desired clearance between plates 15-16.

Hydraulic force in the right hand end of the chamber 56 holds the piston bearing 49 to a seat on the post 61 and such force is made resilient by means of a pressure reservoir (not shown) so that if pieces of metal or other solid particles are inadvertently fed between the plates 15 and 16 the disc 14 can yield by moving to the right a distance required to pass the foreign material from between the discs.

For this purpose the passages 65 extending from the right hand end of the chamber 56 through the plate 57 and the bearing bushing 31 also communicate with a pressure fluid reservoir, not shown. From the left hand end of chamber 56, the pipe 67 communicates through a metered check valve 66 with the tank (not shown). The check valve 66 is arranged so that fluid leaving the left hand end of chamber 56 is restricted in flow by an orifice through the check but flow into the chamber is unrestricted. If during operation of the machine an axial impulse in a right hand direction is imparted to the shaft 23, the pressure in the right hand end of chamber 56 rises above the normal value. This results in passage of some of the hydraulic fluid out of the chamber 56 by way of passages 65, allowing the piston bearing 49 to move in a right hand direction a distance measured by the volume of displaced fluid. During this movement, fluid enters the left hand end of chamber 56 through passage 67 and check valve 66. When the applied axial thrust is released, the piston bearing is returned by hydraulic pressure continuously supplied the chamber 56 at its right hand end, to a position of abutment with the screw post 61. The speed of travel of the piston bearing is limited by the escape of hydraulic fluid from the left end of chamber 56 through the orifice in check valve 66 and thereby avoids damage to the machine when the piston bearing contacts the screw post 61.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described our invention, we claim:

1. A disc mill, including a relatively stationary housing, a pair of grinding discs in adjacent parallel relation, a shaft extending longitudinally through said grinding discs, and projecting at its opposite ends beyond said shaft, one of said discs being secured to said shaft, a radial bearing in said housing for one projecting end of said shaft, a tubular sleeve extending from the other one of said discs in surrounding spaced relation to the other projecting end of said shaft and supported in said housing, a radial

bearing in said tubular sleeve for the other projecting end of said shaft, said tubular sleeve being supported in said housing for relative rotary motion, and means for releasably holding said tubular sleeve in selected positions of rotary adjustment.

2. A disc mill, including a base, a pair of coaxial grinding discs supported thereon, one a rotating disc and the other a relatively stationary disc, an enclosure for said discs including an annular ring arranged for longitudinal sliding movement relative to said enclosure, said ring being slid able to an open position providing access to said discs, a rotatably adjustable mounting for said stationary disc whereby successive portions of said disc may be brought to a position of access, and means for maintaining said annular ring in closed position relative to said enclosure.

3. A disc mill, including a stationary housing, a pair of coaxial grinding discs, a rotatable shaft extending through said discs and having its opposite ends projecting on opposite sides thereof, one of said discs being secured to said shaft, a radial bearing in said housing for the projecting end of said shaft adjacent to said last named disc, a tubular superstructure secured to the other one of said discs and extending in surrounding spaced relation to the other projecting end of said shaft to a rotary mounting in said housing, a radial bearing for the other projecting end of said shaft in said superstructure, and means for holding said superstructure against rotation relatively to said housing.

4. A disc mill according to claim 3, characterized by an annular access door surrounding said discs and detachably anchored to said tubular superstructure at a plurality of circumferential points thereon, the said means for holding said superstructure against rotation being releasable for rotation of said tubular superstructure and associated disc to bring successive portions of said disc to a position of access.

5. A disc mill, including a stationary base, longitudinally spaced apart bearing supports rising from said base and defining therebetween a refining area, the upper ends of said supports having concave bearing surfaces, a pair of relatively rotatable grinding discs in said area, an open ended sleeve received in the bearing surface on one of said supports and united at its one end with the rear of one of said grinding discs, a radial bearing in the concave bearing surface on the other one of said supports, another radial bearing in said sleeve, and a shaft extending axially through said grinding discs and connected to the other one of said discs for unison rotation, the opposite ends of said shaft being received in said radial bearings

and rotatably supported therein, the radial bearing in said sleeve spacing said sleeve from said shaft, one end of said shaft extending through and beyond the radial bearing in said sleeve, a piston on said one end of said shaft, the opposite end of said sleeve being closed and the space beyond said piston being filled with a hydraulic fluid whereby to provide in said sleeve a thrust bearing for said shaft.

5 6. A disc mill according to claim 5, characterized in that the other end of said shaft extends through and beyond the radial bearing in the said other one of said supports, said other end of the shaft being adapted for connection with power rotating means for said shaft.

10 7. A disc mill, including a stationary base, longitudinally spaced apart bearing supports rising from said base and defining therebetween a refining area, a pair of relatively rotatable grinding discs in said area, a sleeve received in one of said supports and united at its one end with the rear of one of said grinding discs, a radial bearing in said sleeve and another radial bearing in the other one of said supports, a shaft extending between and supported in said bearings, said shaft passing through said discs and being connected to the other one thereof for unison rotation, a housing enclosing said discs including 15 a housing component secured to the said other one of said supports and a ring resting on its one end on said housing component and detachably connected at its other end to the assembly comprising said sleeve and said one disc said ring when detached from said assembly being slideable on said housing component to expose said discs for access thereto.

20 8. A disc mill according to claim 7, characterized by means for releasably holding the assembly comprising said sleeve and said one disc against rotation in said one support, said assembly being rotatable when said ring is detached from said sleeve for access to all parts of said one disc.
